(57) **CLAIM**

The ornamental design for a touch screen for automobile, as shown and described.

DESCRIPTION

1. Touch screen for automobile
1.1 is a front perspective view of a touch screen for automobile showing the new design;
1.2 is a front view thereof;
1.3 is a back view thereof;
1.4 is a left view thereof where the right view is a mirror image;
1.5 is a top view thereof;
1.6 is a bottom view thereof;
1.7 is a back perspective view thereof; and
1.8 is another front perspective view of the touch screen for automobile shown installed on a seat of an automobile.
The broken lines depict portions of the touch screen for automobile that form no part of the claimed design; the dash-dot broken lines define the boundary of the claimed design and form no part thereof; the broken lines in 1.8 show an automobile seat that forms no part of the claimed design.
